MECHANICAL TOY

Filed Jan. 16, 1930

UNITED STATES PATENT OFFICE

JOSEPH BULKOWSKI, OF CHICAGO, ILLINOIS

MECHANICAL TOY

Application filed January 16, 1930. Serial No. 421,132.

This invention relates to mechanical toys, the principal object thereof being the provision of a toy having a plurality of platforms which could rotate in opposite directions.

5 A further object of the invention is the provision of a mechanical toy with a plurality of turning platforms of graduated size and in which the platforms may turn in opposite directions.

10 With the above general objects in view and others that will appear as the nature of the invention is better understood, the same consists in the novel combination, construction and arrangement of parts hereinafter more 15 fully described, illustrated in the accompanying drawing and pointed out in the appended claims.

In the drawing forming a part of this application, and in which like designating 20 characters refer to corresponding parts throughout the several views,

Fig. 1 is a cross-sectional view on vertical plane through the toy; and

Fig. 2 is a top plan view, taken on line 2—2 25 of Fig. 1.

Referring in detail to the drawing there is shown therein base 10 having in its center rigidly embedded therein the reduced end 11 of stationary post 12. Mounted upon said 30 base 10 near the edge thereof is an annular wall 13 enclosing the mechanism positioned upon and above said base 10 which will be hereinafter described. Positioned above said base 10 is a turn-table or platform 35 14 which is substantially on the plane with the upper edge of annular wall 13, said platform 14 having flange 15 at its edge downwardly depending therefrom. Rigidly affixed on the underface of said plat- 40 form and set upon post 12 is a bevel gear 16 having an integrally formed and downwardly depending collar 17 resting upon bearing 18 which is rigidly affixed to post 12.

Passing through annular wall 13 is shaft 45 19 terminating at its outer end in crank handle 20, and having at the opposite end a small bevel gear 21 meshing with larger gear 16. Standard 23' positioned near gear 21 forms a bearing for shaft 19.

50 A number of U-shaped plates 23 affixed at

the horizontal portions by means of screws 24 to base 10 are provided to receive at the upper ends rollers 25 which contact with the underface of platform 14 for supporting said platform and maintaining the same in its uniform rotary movement.

Positioned above platform 14 are four rods 26 which are arranged in cross-wise formation and by their inner ends rigidly affixed to post 12. At their outer ends said rods 26 carry freely rotatable rollers 27, made preferably of rubber or other suitable frictional material, said rollers contacting with the upper face of platform 14.

Positioned above said platform 14 is another platform 28 of a smaller diameter resting upon said rollers 27. Said platform 28 is provided at its edge with downwardly depending flange 29.

Another set of four rods 30 rigidly affixed by their inner ends to post 12 is positioned above said platform 28, said rods carrying at their outer ends similar freely rotatable rollers 31 which contact with the upper face of platform 28. Resting upon said rollers 31 is a third platform 32 which is of a smaller diameter than the lower platform 28. Said last mentioned platform 32 has a similar downwardly depending flange 33 at its edge.

Positioned above said platform 32 is another set of four rods 34 arranged in cross-wise formation and by their inner ends rigidly affixed to post 12, which rods carry at their outer ends freely rotatable rollers 35 contacting with platform 32, and supporting a fourth platform 36 provided with a similar downwardly depending flange 37 at its edge.

Positioned above said platform 36, but not contacting therewith is an observation block 38 rigidly affixed to post 12 by means of pin 39.

As already stated, said platforms 14, 28, 32 and 36, as well as the observation block 38, are of graduated diameters, and when the same are in an operative relation they have a conical arrangement, as clearly seen on Fig. 1. Thus, each platform, with relation to the next platform of a smaller diameter, has an annular free space adjacent its edge upon which a number of figures 40, 50

representing marching soldiers, horses, ordnances, and the like, are arranged in round formation.

Post 12, adjacent its upper end has a ring 41 rigidly affixed thereto by pin 42, constituting a bearing for a freely rotatable ring 43 set upon post 12 and carrying a plurality of radially arranged wire loops 44, which, by their inner ends are rigidly affixed to ring 43, and by their outer, downwardly inclined ends support and carry toy aeroplanes 45. One of said loops 44 has a rigid wire 46 connecting to one of the figures on platform 14.

Placed upon the upper end of said post 12 is a roof 47 which is further supported by means of a number of standards 48, which by their lower ends are rigidly affixed to base 10, as at 49.

Said annular wall 13 at its lower edge is provided with a horizontal flange 50 which rests upon base 10 and by means of which said wall 13 is rigidly affixed to said base 10 through the medium of screws 51.

Referring to the operation of the invention, it is observed that each set of rollers 27, 31 and 35 is in frictional contact with platforms which are below and above each respective set of said rollers.

Therefore, assuming that crank 20 is turned into a direction to cause platform 14 to turn, through the medium of gears 21 and 16, to the direction indicated by an arrow on Fig. 2, rollers 27 will rotate in the reverse direction, and the direction of rotation of said rollers 27 will be imparted to platform 28, which will turn in the reverse direction from that of platform 14, since, as already stated, said rollers 27 are in frictional contact with the upper face of platform 14 and with the underface of platform 28. A similar operation will take place with platform 32 to which the reverse direction of rotation from that of platform 28 will be imparted through the medium of rollers 31 which are in frictional contact with the upper face of platform 28 and with the underface of platform 32. Thus, said platform 32 will turn to the direction opposite from that of platform 28, but to the same direction with platform 14. Platform 36 will then turn to the direction opposite from that of platform 32 but the same as of platform 28, due to the reverse transmission of movement through the medium of rollers 35 which remain in frictional contact with the upper face of platform 32 and the under face of said platform 36. Therefore, said four platforms in said assumed case will rotate to the directions indicated by arrows on Fig. 2. Observation block 38 will remain stationary as already stated. It is to be understood that through the center of each of said platforms passes post 12 around which said platforms rotate.

From the hereinabove description it will be seen that when said four platforms rotate

in alternate directions, figures 40 arranged upon said platforms will present a striking appearance and a mass of movement since said figures rotate with their respective platforms. Due to the connection of wires 46 between platform 14 and loops 44 and the aeroplane toys 45 will likewise rotate to the same direction to which platform 14 rotates.

While there is described herein a preferred embodiment of the present invention it is nevertheless to be understood that minor changes may be made therein without departing from the spirit and scope of the invention as claimed.

What I claim as new is:

1. A mechanical toy comprising a plurality of platforms of graduated diameters, a post passing through said platforms and around which the latter are adapted to rotate, a gear affixed to one of said platforms, a crank shaft, a gear positioned upon said crank shaft and meshing with the first named gear, and rollers in frictional contact with each pair of adjacent platforms.

2. A mechanical toy comprising a plurality of platforms of graduated diameters, a post around which the same are positioned and adapted to rotate, a plurality of sets of rods rigidly affixed to said post, each set of said rods being interposed between each adjacent pair of said platforms, freely rotatable rollers carried by each set of said rods, each set of rollers being in frictional contact with each pair of adjacent platforms, means for supporting said platforms, and means for imparting a rotary movement to one of said platforms.

In testimony whereof I affix my signature.

JOSEPH BULKOWSKI.
